UNITED STATES PATENT OFFICE.

CHARLES E. BERTELS, OF WILKESBARRE, PENNSYLVANIA.

DESIGN FOR A RESERVOIR-COVER FOR RECEPTACLES.

SPECIFICATION forming part of Design No. 34,169, dated March 5, 1901.

Application filed February 6, 1901. Serial No. 46,269. Term of patent 7 years.

To all whom it may concern:

Be it known that I, CHARLES E. BERTELS, a citizen of the United States, residing at Wilkesbarre, in the county of Luzerne and State of Pennsylvania, have invented and produced a new and original Design for a Reservoir-Cover for Receptacles, of which the following is a specification.

The leading or material feature of the design resides in a reservoir-cover for receptacles, having a top from the central portion of which an upstanding neck projects, the outer face of said top being provided with a plurality of ribs that radiate from the neck.

In the drawings, Figure 1 is a perspective view of a cover embodying the new design. Fig. 2 is a side elevation of the same. Fig. 3 is a top plan view.

In said drawings the reservoir-cover is designated as a whole by the reference-numeral

10, and consists of side walls and a dome-shaped top, the meeting edges of said side walls and top being provided with the usual outstanding flange.

The top of the reservoir-cover is provided with the centrally-disposed upstanding neck 11, and is also provided with a plurality of ribs 12, that radiate from said neck.

Having described the invention, what I claim as new, and desire to secure by Letters Patent, is—

The design for a reservoir-cover for receptacles, as herein shown and described.

In testimony that I claim the foregoing as my own I have hereto affixed my signature in the presence of two witnesses.

CHARLES E. BERTELS.
